(57) **CLAIM**

The ornamental design for a stationary base of a medical line organizer, as shown and described.

DESCRIPTION

FIG. 1 is an isometric view of the stationary base of the medical line organizer, showing my new design;

FIG. 2 is a front elevational view of the stationary base of the medical line organizer of FIG. 1, the rear elevational view being a mirror image thereof;

FIG. 3 is a right elevational view of the stationary base of the medical line organizer of FIG. 1, the left elevational view being a mirror image thereof;

FIG. 4 is a top plan view of the stationary base of the medical line organizer of FIG. 1;

FIG. 5 is a bottom plan view of the stationary base of the medical line organizer of FIG. 1; and,

FIG. 6 is an isometric view of the stationary base of the medical line organizer and a detachable exemplary top of a medical line organizer decoupled from each other.

The portions of the stationary base of a medical line organizer shown in broken lines form no part of the claimed design. The other broken lines illustrate exemplary environmental subject matter that form no part of the claimed design.
